J. M. BLANCHARD,
SHIPPING BOX,
APPLICATION FILED NOV. 12, 1917.

1,319,835.

Patented Oct. 28, 1919.

UNITED STATES PATENT OFFICE.

JULIUS M. BLANCHARD, OF CHICAGO, ILLINOIS.

SHIPPING-BOX.

1,319,835.

Specification of Letters Patent. Patented Oct. 28, 1919.

Application filed November 12, 1917. Serial No. 201,629.

To all whom it may concern:

Be it known that I, JULIUS M. BLANCHARD, a citizen of the United States, and a resident of Chicago, in the county of Cook and State 5 of Illinois, have invented certain new and useful Improvements in Shipping-Boxes, of which the following is a full, clear, and exact description.

The invention relates to shipping boxes 10 and more particularly to those in which the body or top, bottom and sides are formed of sheet material, such as fiber or corrugated board and the end-pieces are separately formed of similar material and provided 15 with cleats for interlocking with cleats on the body.

One object of the invention is to provide an improved box of this type in which the box-ends are removably secured in place by 20 cleats on the end-pieces of the box-sides and in which the cleats on the top or bottom of the box have their ends interlocked with the ends of both the cleats on the sides and the ends, so that, as the result of this interlocking, cross cleats on the ends to interlock 25 with the cleats on the top and bottom may be dispensed with.

Another object of the invention is to provide an improved box of this character which 30 can be produced at a low cost, which is simple in construction and is adapted to withstand severe handling in shipping.

The invention consists in the several novel features hereinafter set forth and more particularly defined by claims at the conclusion hereof.

In the drawings: Figure 1 is a perspective of a box embodying the invention, one of the ends being raised from the remainder 40 of the box. Fig. 2 is a horizontal section. Fig. 3 is a perspective, upon an enlarged scale, of the interlocking joint between one of the cleats on the top of the box and the cleats on one of the ends and sides. Fig. 45 Fig. 4 is a detail perspective of one of the cleats attached to one of the sides of the box. Fig. 5 is a detail perspective of one of the cleats on one of the box-ends. Fig. 6 is a vertical section taken on line 6—6 of Fig. 3, when 50 the box is closed.

The sides 4 and 5, bottom 6, top 7 and flap 8 are usually formed of a single piece of corrugated or fiber board properly folded and cut. The front and rear sides of 55 the box have secured to their respective inner faces at each end-margin, a vertical

cleat 9. Each of these cleats is secured to the fiber or corrugated board body by suitable devices, usually nails 10, which are driven through the board and into the cleats. 60 The outer face 11 of each cleat 9 is substantially flush with the outer edge of the box-side. Each cleat 9 is formed with a dovetail tongue 12. The space between each tongue 12 and the box-side to which it is attached, forms a groove 14 disposed within the corner between its inner face and the box side, this groove lying wholly within the cleat 9 and being formed by an obtuse angled edge or surface 13 and an inclined 65 face 13'. These grooves 14 are adapted to receive vertical cleats 15 which are secured to the end-pieces 16 which are usually formed of sheet material such as fiber or corrugated board. Each cleat 15 is secured to the 70 outer face of an end-piece 16 adjacent its side margin by nails 17 which are driven through the fiber or corrugated board and into the cleat from the inner side of the board. The outer edge 18 of each cleat 15 75 is substantially flush with the edge of the contiguous cleat 9 which abuts against the box-side and is also flush with the adjacent edge. In the cross-section, the cleat conforms substantially to the groove 14 in one 80 of the cleats 9, being formed with an obtuse angled inner edge 15' conforming to the surface 13 on the cleat 9 and an inclined outer face 15^a corresponding to the face 13' 85 on cleat 9. These inclined surfaces between 90 the cleats 9 and 15 respectively are formed so that each end-piece 16 will be locked against movement longitudinally of the sides and so that the sides will be secured against separating by the box-ends and cleats thereon. A characteristic of this construction is that force applied to spread apart the sides 95 4 and 5 will subject the end-pieces to tensile stresses only and this results from forming inclined locking surfaces between the cleats 100 at the inner side of the cleats 9 adjacent the box sides. A further characteristic of this construction is that the cleats 15 are wholly concealed or disposed within the cleats 9 when the box is assembled. The obtuse angled edges and inclined sides between the cleats 9 and 15 provide an interlocking connection which avoids sharp corners that are 105 easily broken.

Bottom 6 has secured to its upper face at 110 each of its end margins a horizontal or cross cleat 20. The top 7 has secured to its inner

face and at each of its end margins, a horizontal or cross cleat 22. The meeting edges or ends of the cleats 9, 15, 20 and 22 are mutually mitered. At each corner-joint between the horizontal and vertical cleats, cleats 9 and 15 are formed with extensions which together form a tongue 23 which is adapted to extend into a corresponding groove 24 in one of the horizontal cleats, to 10 form an interlocking-connection which prevents relative movement longitudinally of the box, between the vertical and horizontal cleats and between the vertical cleats. This construction exemplifies one in which there 15 is an interlocking joint between the horizontal cleats on the box-body and the vertical cleats on the box end, as well as the side cleat on the box sides. A characteristic of this construction is that the vertical cleats 20 on the box-ends will be securely locked to the cleats on the box-sides and to the cross or horizontal cleats on the body, so that the box, when completed, will be substantially as rigid as when the cross-cleats 25 on the box-ends are used.

In the manufacture of these boxes, the cleats 9, 20 and 22 are usually secured to the end-margins of the body blank and the cleats 15 are secured to the end-pieces or blanks 16 30 at the factory. The parts are shipped to the user in knock-down condition. To assemble the box for use, it is only necessary to fold the sides and bottom into parallel vertical position to receive the end-members. 35 When the cleats 15 have been slipped into operative position in the cleats 9, the several parts of the box will be held in operative position by the end-members and their interlocking connections with the cleats on the 40 body-blank. To close the box, the cover 7 is folded into position over the body. The interfitting tongue and groove connections between the meeting edges of the horizontal cleats on the box body and the vertical cleats, both on the box sides and the box 45 ends will be securely interlocked to give great rigidity to the box. When the flap 8 is secured in position, there will be a complete interlock between the cleats whereby 50 the box will be held firm against the usual stresses.

The invention exemplifies a box formed of a blank of sheet material and ends having vertical cleats which are interlocked directly with the cross cleats on the box-body at their meeting edges and also one in which the vertical cleats on the box ends are wholly confined or disposed within the vertical cleats on the box sides, and one which, 55 when assembled, is unusually rigid.

The invention is not to be understood as restricted to the details set forth, since these may be modified within the scope of the appended claims, without departing from 60 the spirit and scope of the invention.

Having thus described the invention, what I claim as new and desire to secure by Letters Patent, is:

1. In a box, the combination of a body of sheet material comprising sides, vertical cleats secured to the inner end-margins of the box-sides, box-ends, vertical cleats on the ends, the cleats on the ends and sides having longitudinal interfitting and interlocking portions, horizontal cleats on the 75 body, and interlocking connections between the meeting ends of the horizontal cleats and the vertical cleats on the box-ends, formed to secure the vertical and horizontal cleats against relative movement longitudinally of 80 the body.

2. In a box, the combination of a body of sheet material comprising sides, vertical cleats secured to the inner end-margins of the box-sides, box-ends, vertical cleats on 85 the ends, the cleats on the ends and sides having longitudinal interfitting and interlocking portions, horizontal cleats on the body, and interlocking connections between the meeting ends of the horizontal cleats 90 and the vertical cleats on the box-ends and on the box-sides, formed to secure the vertical and horizontal cleats against relative movement longitudinally of the body.

3. In a box, the combination of a body of 95 sheet material comprising sides, vertical cleats secured to the inner end-margins of the box-sides, box-ends, vertical cleats on the ends, the cleats on the ends and sides having longitudinal interfitting and interlocking portions, horizontal cleats on the body, mitered meeting ends between the horizontal cleats and the vertical cleats on the box ends and interlocking, and interfitting tongue and groove connections between 100 said mitered meeting ends formed to secure the vertical and horizontal cleats against relative movement of the body.

4. In a box, the combination of a body of 110 sheet material comprising sides, vertical cleats secured to the inner end-margins of the box sides, box-ends, vertical cleats on the ends, cleats on the ends and sides having longitudinal interfitting and interlocking portions, horizontal cleats on the 115 body, mitered meeting ends between the horizontal cleats and the vertical cleats on the box sides and interlocking and interfitting tongue and groove connections between the mitered ends of the horizontal cleats and the vertical cleats on the ends and sides formed to secure vertical and horizontal cleats against relative movement longitudinally of the body.

5. In a box, the combination of a body 125 of sheet material comprising sides, vertical cleats secured to the inner end margins of the sides, box-ends disposed at the inner faces of the vertical cleats on the sides, and vertical cleats fixed to the outer faces of 130

the end-margins of the box-ends, the vertical cleats on the sides having grooves formed in their inner corners and adjacent the sides, conforming to the vertical cleats 5 on the box ends, the vertical cleats on the ends and sides thus having longitudinal interfitting and interlocking portions.

6. In a box, the combination of a body of sheet material comprising sides, vertical 10 cleats secured to the inner end margins of the sides, box-ends disposed at the inner faces of said vertical cleats, cleats fixed to the end-margins and outer faces of the box-ends, the vertical cleats on the sides having 15 grooves at their inner corners adjacent the sides conforming to the vertical cleats on the box ends, the vertical cleats on the ends and sides thus having longitudinal interfitting and interlocking portions including obtuse 20 angled contiguous faces.

7. In a box, the combination of a body of sheet material comprising sides, vertical cleats secured to the inner end margins of the sides, box-ends disposed at the inner 25 faces of said vertical cleats, and vertical cleats fixed to the end-margins and outer faces of the box ends, the vertical cleats on the sides having grooves at their inner corners adjacent the box-sides conforming to 30 the vertical cleats on the box ends, the vertical cleats on the ends and sides having lon-

gitudinal interfitting and interlocking portions, including obtuse angled and inclined contiguous surfaces.

8. In a box, the combination of a body of 35 sheet material comprising sides, vertical cleats secured to the end margins of the sides, box-ends, vertical cleats on the ends, the cleats on the ends and the sides having longitudinal interlocking portions, the cleats on 40 the ends being disposed wholly within the cleats on the sides, horizontal cleats on the body, and interfitting and interlocking connections between the meeting ends of all the vertical cleats and the horizontal cleats, 45 formed to secure the vertical and horizontal cleats against relative movement in the body.

9. In a box, the combination of a body of sheet material comprising sides, vertical cleats secured to the end margins of the 50 sides, box-ends, vertical cleats on the ends, the cleats on the ends and the sides having longitudinal interlocking portions, the cleats on the ends being disposed wholly within the cleats on the sides, horizontal 55 cleats on the body, and tongue and groove connections between the ends of the horizontal cleats and the ends of the vertical cleats on the sides and on the ends, formed to secure the vertical and horizontal cleats 60 against relative movement in the body.

JULIUS M. BLANCHARD.
